UNITED STATES PATENT OFFICE

158,439

ELECTRIC DEEP FAT FRYER

Stanley J. Budlane and Robert Dusek, Chicago,
Ill., assignors to Dulane, Inc., River Grove, Ill.,
a corporation of Illinois

Application August 27, 1949, Serial No. 4,734

Term of patent 14 years

(Cl. D81—10)

To all whom it may concern:

Be it known that we, Stanley J. Budlane and Robert Dusek, both citizens of the United States and residents of Chicago, in the county of Cook and State of Illinois, have invented a new, original, and ornamental Design for an Electric Deep Fat Fryer, of which the following is a specification, reference being had to the accompanying drawing, forming a part thereof.

Figure 1 is a perspective view of the electric deep fat fryer with the cover in place, embodying our new design.

Figure 2 is a top plan view, thereof.

Figure 3 is a side view, thereof.

Figure 4 is a front view, thereof.

Figure 5 is a perspective view of the electric deep fat fryer with the cover removed, and

Figure 6 is a top plan view of Figure 5.

We claim:

The ornamental design for an electric deep fat fryer, substantially as shown.

STANLEY J. BUDLANE.
ROBERT DUSEK.
